UNITED STATES PATENT OFFICE.

JOHN WARWICK GORDON, OF ST. CATHARINES, ONTARIO, CANADA.

TOY GUN.

1,215,926.

Specification of Letters Patent.

Patented Feb. 13, 1917.

Application filed April 3, 1916. Serial No. 88,504.

To all whom it may concern:

Be it known that I, JOHN WARWICK GORDON, of the city of St. Catharines, in the county of Lincoln, in the province of Ontario, Canada, have invented certain new and useful Improvements in Toy Guns, of which the following is the specification.

My invention relates to improvements in toy guns or cannons and the object of the invention is to devise a gun adapted to shoot marbles or like projectiles which is provided with a magazine which will automatically feed the marbles from the magazine into the breech after each shot, which may be sighted and held firmly in the sighting position until after the shot and yet which will automatically move from the sighting position after each shot and it consists essentially of a barrel body provided with a main barrel bore, a spring actuated plunger rod located in the main barrel bore, a supplemental bore also extending longitudinally through the barrel body and terminating intermediate of the length of the main barrel bore in an orifice extending in a vertical forwardly inclined direction from the exterior of the barrel body into the bore, friction means for holding the marbles in position in the bore in front of the plunger, trigger means for holding the plunger in the withdrawn position and an adjustable back sight as hereinafter more particularly explained by the following specification.

Figure 1, is a general perspective view of my gun.

Fig. 2, is a longitudinal section through the center of the gun.

Fig. 3, is a vertical section on line $x-y$ Fig. 2.

Fig. 4, is an enlarged detail of the retaining means for holding the marbles in the main bore in front of the plunger rod.

Fig. 5, is an enlarged detail of the means for frictionally holding the barrel body in the vertically swung position.

Fig. 6, is a plan section of the rear portion of the barrel body on line $x'-y'$.

In the drawings like letters of reference indicate corresponding parts in each figure.

1 indicates a carriage comprising the side members 2 and 3 connected together by cross bars 4 and 5. 6 indicate hubs formed at the inner end of the arms 2 and 3 and provided with central orifices 7. The arms 2 and 3 are provided with upward extensions 8 di-

rected upwardly from the hub 6, the upper ends of such extensions being provided with orifices 9. 10 indicates the barrel body, the inner end of which is enlarged for a purpose which will hereinafter appear.

12 indicates the main bore of the barrel body. 13 indicates a plunger rod fitting within the barrel bore 12 and designed to move longitudinally thereof. The rear end of the rod 13 projects outwardly at 14 from the barrel bore and is provided with a cross head 15. 16 indicates a supplemental bore located below the main bore 12 and extending longitudinally of the barrel body. 17 indicates a recess formed in the lower portion of the head 15. 18 indicates a tension spring secured at one end within the recess 17 and at the opposite end within the inner end of the bore 16. The barrel body 10 is provided with trunnions 19 extending into the orifices 9 hereinbefore referred to. By this means the barrel body is swung so that the muzzle of the barrel may be moved upwardly or downwardly in a vertical direction.

20 indicates the magazine bore which extends longitudinally in a slightly forwardly and downwardly inclined direction. 21 indicates a vertical forwardly inclined orifice extending through the barrel body into the barrel bore intermediate of its length and into which the magazine bore 20 extends intermediate of its height. 22 indicates an inclined pin extending through the upper portion of the barrel body so as to project in front of the rear mouth of the magazine bore 12 and prevent the marbles passing outwardly through such mouth. 23 indicates a pad of resilient material secured to the upper portion of the cross head 15 so as to fit over the rear mouth of the barrel bore 20. 24 indicates a vertical orifice extending through the barrel body in front of the orifice 21. The lower end of the orifice 24 is slightly constricted at 25 and 25^x indicates a marble fitting within such orifice and resting upon the constricted end of the orifice so that the lower peripheral portion of the marble projects inwardly into the main bore 12 when the plunger rod 13 is withdrawn.

26 indicates a retaining pin extending diametrically of the upper end of the orifice 24 so as to prevent the withdrawal of the marble 25^x. 27 indicates an arc-shaped 110

spring bar secured to the rear end of the barrel body and extending through an orifice 28 formed in the cross bar 5. The lower end of the bar 27 is provided with a turned end 29 forming a stop preventing the withdrawal of the spring bar 27 from the orifice 28. 30, 31 and 32 indicate spring members which bear against the bar 27 so as to frictionally engage the same and prevent free movement of the bar 27 and yet allow of easy movement when the rear end of the barrel body is depressed or elevated. 17^x indicates a cross recess formed in the rear end of the barrel body. 34 indicates a retaining pin extending vertically across the recess 17^x at one side of the barrel body. 35 indicates a spring finger or trigger which extends horizontally through the recess 17^x between the retaining bar 34 and the base of 20 the recess. The outer end of the trigger 35 is provided with a suitable turned end forming a handle. The trigger 35 is provided with a right angularly bent portion which extends longitudinally of the barrel body, 25 and is secured thereto by suitable means and the opposite end of the trigger enters an orifice in the barrel body at right angles and provides the spring power to the trigger. 36 indicates a recess formed in the plunger 30 rod 13 and adapted to engage with the trigger 35 when the plunger rod is withdrawn. 38 indicates the foresight consisting of a pin or other suitable projecting portion carried by the muzzle end of the barrel body. 39 35 indicates the back sight comprising an inverted U-shaped bar member having a V-shaped depression 40 formed in the base of the U. The arms 41 and 42 of such U-shaped member extend through vertical orifices 43 formed at each side of the barrel body 11 and frictionally engaging the walls of the orifices. 44 indicates the axle extending through the orifices 7 and 45 are the carrying wheels. 45 Having described the principal parts involved in my invention I will briefly describe the operation of the same.

In order to sight the gun for the required range the inner end of the barrel body is 50 either depressed or raised and the back sight 39 adjusted vertically so that the foresight 38 is seen on a line with the mark desired to be hit through the V-shaped portion 40 of the rear sight 39. The plunger 13 is withdrawn until the forward end is located on the dotted line 44^x, the trigger 35 engaging in the forward end of notch 36 in the plunger rod, it being prevented thereby from further backward motion. This allows the 55 forward marble of the series 45^x contained in the magazine bore 20 to pass down through the orifice 21 into the main bore 12, and allowing the marble 25^x to drop far enough into the main bore 12 to prevent the 60 said projectile from rolling out of the bar- 65

rel. The plunger 13 is then released pushing the fed marble forwardly in the bore 12 into contact with the downwardly projecting portion of the periphery of the marble 25^x. This forward movement of the plunger carries the front end thereof into the position indicated by dotted line 46, the trigger 35 being then located against the shoulder formed by the rear end of the notch 36. In this position the end of the plunger does not bear upon the fed marble, such marble being held from passing forwardly in place within the bore by the weight 25^x. When the gun has been sighted and is ready to fire all that it is necessary to do is to press the trigger 35 thus freeing the plunger rod 13 which is carried forcibly forward by the spiral spring 18, such forcible forward movement carrying the fed marble past the marble 25^x by raising the same from the 70 dotted position shown in Fig. 2 to the full position shown in the same figure. The marble is then ejected from the muzzle of the gun. As the plunger rod 13 passes forward or is drawn back through the barrel bore 12 the marble 25^x rests on top of the plunger rod 13 and rolls freely thereon within the vertical orifice 24 thus causing no 75 friction and consequent loss of driving power to the plunger rod 13. If the gun is 80 in a horizontal position or the muzzle of the gun is depressed it will be readily seen that the next succeeding marble in the magazine will roll forwardly into the orifice 21 and 85 on to the rod 13 ready to be fed into position 90 into the barrel bore 12 when the plunger rod 13 is again withdrawn. If, however, as is usually the case, the muzzle of the gun is elevated the next succeeding marble is fed 95 forward by the impact of the pad 23 carried by the upper portion of the head 15 carried by the rear end 14 of the plunger rod 13 against the rearmost marble of the series 45^x, the peripheral portion of which projects 100 through the rear mouth of the magazine bore 20 as indicated by dotted lines in Fig. 2. The impact upon the rearmost ball of the series 45^x forces the whole series of balls 105 forward until the foremost ball enters the orifice 21 and into the feeding position upon 110 the plunger rod 13, this marble being fed into the position for firing when the plunger rod is next withdrawn. 115 In order that the elevation may automatically change after the shot has been fired it 120 will be noted that the rear end of the barrel body is frictionally supported by the spring bar 27 held in position by the spring bars 30, 31 and 32. When the gun is fired the shock of the cross head coming against 125 the end of the barrel body is sufficient to overcome the frictional contact of the bars 30, 31 and 32 against the bar 27 and move such bar 27 so as to allow the barrel body to 130 swing out of the sighting position.

It will thus be seen that it will be impossible for a person to sight the gun so as to hit the bull's eye and then repeat shot after shot against the same mark. After each shot the gun must be resighted thereby calling upon the skill of the user for every individual shot.

In order to sight the gun all that it is necessary to do is to raise the back sight in accordance with the distance of the object and then sight the gun in the usual way by bringing the foresight into a line with the V-shaped recess of the back sight.

From this description it will be seen that I have devised a simple form of toy gun which must be sighted for each individual shot, in which the marbles which are used as projectiles are automatically fed from the magazine into the breech by the impact when firing each shot, and from the breech into the firing position in the barrel by the withdrawal of the plunger after each shot and in which the marble fed to the firing position within the barrel body is held in position ready for firing no matter whether the barrel bore is inclined upwardly or downwardly, and in which simple sighting means is provided which may be adjusted to suit each individual user of the gun.

What I claim as my invention is:

1. In a toy gun, the combination with the barrel body provided with a barrel bore and a vertical orifice extending through the barrel body into the bore intermediately of the length of the same, a spring plunger held in the barrel bore and designed to be withdrawn to a position to the rear of the aforesaid orifice, means for feeding a series of marbles into the barrel bore between the withdrawn end of the plunger and the aforesaid orifice, and a ball freely supported within the orifice and having a spherical peripheral portion projecting downwardly through such orifice into the barrel bore and into contact with the fed marble.

2. In a toy gun, the combination with the barrel body having a barrel bore and an orifice extending vertically through the body into the bore, and a magazine bore extending through the barrel body from the rear thereof into the vertical orifice at its opposite end and adapted to hold a series of marbles, of a spring plunger held within the barrel bore, and means for producing impact upon the rearmost marble in the magazine simultaneously with the forward or firing movement of the spring plunger to carry the foremost marble into the vertical orifice.

3. In a toy gun, the combination with the barrel body having a barrel bore and a forwardly inclined vertical orifice extending vertically through the body into the bore, and a magazine bore extending through the barrel body from the rear thereof into the

vertical orifice at its opposite end and adapted to hold a series of marbles, of a spring plunger held within the barrel bore, and means for producing impact upon the rearmost marble in the magazine simultaneously with the forward or firing movement of the spring plunger to carry the foremost marble into the vertical orifice.

4. In a toy gun, the combination with the barrel body having a barrel bore and an orifice extending vertically through the body into the bore, and a magazine bore extending through the barrel body from the rear thereof into the vertical orifice at its opposite end and adapted to hold a series of marbles, of a spring plunger held within the barrel bore, and means for producing impact upon the rearmost marble in the magazine simultaneously with the forward or firing movement of the spring plunger to carry the foremost marble into the vertical orifice, and means located at the rear end of the magazine bore for retaining the marbles therein.

5. In a toy gun, the combination with the barrel body having a barrel bore and an orifice extending vertically through the body into the bore, and a magazine bore extending through the barrel body from the rear thereof into the vertical orifice at its opposite end and adapted to hold a series of marbles, of a spring plunger held within the barrel bore, retaining means located at the rear end of the magazine bore for holding the marbles within the bore and yet allowing the peripheral portion of the rearmost marble to project from the mouth, a cross head carried by the spring operated plunger adapted to be carried against the peripheral portion of the rearmost ball when the plunger is fired.

6. In a toy gun, the combination with the barrel body having a barrel bore and an orifice extending vertically through the body into the bore, and a magazine bore extending through the barrel body from the rear thereof into the vertical orifice at its opposite end and adapted to hold a series of marbles, of a spring plunger held within the barrel bore, retaining means located at the rear end of the magazine bore for holding the marbles within the bore and yet allowing the peripheral portion of the rearmost marble to project from the mouth, and a cross head carried by the spring operated plunger and provided with a resilient pad adapted to be carried against the projecting peripheral portion of the rearmost ball when the plunger is fired.

7. In a toy gun, the combination with the barrel body having a barrel bore and having a vertical orifice extending through the body into the bore intermediately of its length and having a magazine bore extending longitudinally of the body into the

the orifice intermediately of its height, of frictional retaining means depending into the barrel bore in front of the aforesaid orifice, a spring trigger carried by the rear end of the barrel body, a spring plunger operating within the barrel bore and having a longitudinal recess in its lower peripheral portion equal in length to the distance between the orifice opening into the barrel bore and frictional retaining means and through the forward end of which the trigger extends when the plunger is in the completely withdrawn position.

8. In a toy gun, the combination with the barrel body swingably mounted in a suitable carriage and having a foresight, of a vertically adjustable backsight comprising an inverted U-shaped member, the vertically extending arms of which are frictionally held

20 by the barrel body and having a V-shaped depression in the base portion of the U.

9. In a toy gun, the combination with the

barrel body swung upon a suitable carriage and provided with a foresight and having vertical orifices extending through the rear portion of the body at each side thereof, of an inverted U-shaped rear sight having the arms thereof frictionally held within such orifices and having a V-shaped depression in the base or horizontal portion of the U.

25

30

10. In a toy gun, the combination with the barrel body and a suitable carriage upon which the body is swung, of a cross bar swung upon the carriage having a diametric orifice, an arc-shaped spring member carried by the barrel body and extending through such diametric orifice, and spring fingers carried by the carriage and bearing upon the spring member.

JOHN WARWICK GORDON.
